Primary Examiner — Kimberly Barnes*Assistant Examiner* — Sarah A Nguyen(74) *Attorney, Agent, or Firm* — Sand, Sebolt & Wernow Co., LPA(57) **CLAIM**

The ornamental design for an apparatus for pet hair removal, as shown.

DESCRIPTION

FIG. 1 is a front, top, left side isometric perspective view of an apparatus for pet hair removal in accordance with my design;

FIG. 2 is a front, top, right side isometric perspective thereof;

FIG. 3 is a front elevation view thereof;

FIG. 4 is a left side elevation view thereof;

FIG. 5 is a top plan view thereof; and,

FIG. 6 is a bottom plan view thereof.

The broken lines illustrate portions of the apparatus for pet hair removal which form no part of the claimed design. The claimed design is shown with a symbolic break in its length. The appearance of any portion of the article between the break lines forms no part of the claimed design.

1 Claim, 5 Drawing Sheets# US D1,032,137 S
